UNITED STATES PATENT OFFICE.

GABRIEL A. BOBRICK, OF BOSTON, MASSACHUSETTS.

DESIGN FOR A PEDESTAL FOR FURNITURE.

SPECIFICATION forming part of Design No. 26,715, dated March 2, 1897.

Application filed January 25, 1897. Serial No. 620,696. Term of patent 7 years.

To all whom it may concern:

- Be it known that I, GABRIEL A. BOBRICK, a citizen of the United States, residing at Boston, in the county of Suffolk and State of Massachusetts, have invented and produced a new and original Design for Furniture-Pedestals, of which the following is a specification, reference being had to the accompanying drawings, forming part thereof.
- 10 Figure 1 of the drawings shows in front elevation a furniture-pedestal illustrating my design, and Fig. 2 is a perspective view thereof.
- The leading feature of my design for a furniture-pedestal consists in a hollow head having flattened front and rear faces, with an aperture in each, the sides of the head being convexed, said head surmounting an upright columnar standard, flaring at its lower end and terminating in an annular base.
- 15 20 In the drawings the annular base A is shown as sweeping up in an easy curve, as at a, to the upright columnar standard B, presenting a substantially bell-shaped body portion.

The top of the standard is set in at front and back, at b b', at the base of a hollow head C, 25 having flattened front and rear faces c c' of unequal width, the convex sides c² being shown in direct continuation of the curved surface of the standard, the flattened faces of the head being apertured at c³c⁴, respectively. 30

The general configuration of the pedestal is at once pleasing and striking, giving the effect of combined strength and lightness.

Having fully described my invention, what I claim, and desire to secure by Letters Patent, is—

The design for a furniture-pedestal, substantially as herein described.

In testimony whereof I have signed my name to this specification in the presence of 40 two subscribing witnesses.

GABRIEL A. BOBRICK.
